CLAIM

The ornamental design for headphones' earpiece, as shown and described.

DESCRIPTION

FIG. 1, shows a top perspective view of an embodiment of the headphones' earpiece that I claim;
FIG. 2, shows a top perspective view of a second embodiment of the headphones' earpiece that I claim;
FIG. 3, shows a bottom perspective view of the first embodiment of the headphones' earpiece that I claim;
FIG. 4, shows a bottom perspective view of a second embodiment of the headphones' earpiece that I claim;
FIG. 5, shows a right side view of the first embodiment of the headphones' earpiece that I claim;
FIG. 6, shows a side view of the second embodiment of the headphones' earpiece that I claim;
FIG. 7, shows a front view of the first embodiment of the headphones' earpiece that I claim;
FIG. 8, shows a bottom view of the second embodiment of the headphones' earpiece that I claim;
FIG. 9, shows a top view of the first embodiment of the headphones' earpiece that I claim, having shading lines indicating metallic surface;
FIG. 10, shows a top view of the second embodiment of the headphones' earpiece that I claim, having shading lines indicating metallic surface;
FIG. 11, shows a bottom view of the first embodiment of the headphones' earpiece that I claim; and,
FIG. 12, shows a bottom view of the second embodiment of the headphones' earpiece that I claim.
The dashed lines shown in FIGS. 1-10, indicate environmental structures and as such, do not form a part of the claimed design.
The break lines shown in FIGS. 1-6, and 9-12, form no part of the claimed design except for indicating indeterminate length.
The stippling on the headphones' earpiece in FIGS. 1-8, 11 and 12 represents surface shading, where a change in the density of stippling of the headphones' earpiece to denote a gradation of the texture of that portion of the headphones' earpiece.
Metal surfaces are shown in FIGS. 1, 2, 9, and 10.
